Fig. 1

Fig. 2

Fig. 3

FIG. 1 is a view in perspective of one embodiment of my ornamental design for a lamp shade.

FIG. 2 is a bottom plan view of the lamp shade embodiment shown in FIG. 1.

FIG. 3 is an enlarged fragmentary detail view in side elevation of the cordage which forms the side surface of said shade.

FIG. 4 is a view in perspective of another embodiment of my ornamental design for a lamp shade.

FIG. 5 is a bottom plan view of the lamp shade embodiment shown in FIG. 4.

FIG. 6 is a view in side elevation of the embodiment of FIG. 4, portions being broken away.

This application is a continuation of my copending application Serial No. D. 447,730, filed February 4, 1957, now abandoned.

I claim:

The ornamental design for a lamp shade, as shown and described.
